UNITED STATES PATENT OFFICE.

EMMA A. TOURNY, OF PHILADELPHIA, PENNSYLVANIA.

DESIGN FOR A GAME-BOARD.

SPECIFICATION forming part of Design No. 28,048, dated December 14, 1897.

Application filed October 4, 1897. Serial No. 654,083. Term of patent 3½ years.

To all whom it may concern:

Be it known that I, EMMA A. TOURNY, residing in the city and county of Philadelphia and State of Pennsylvania, have invented and 5 produced a new and useful Design for a Puzzle or Game-Board, of which the following is a specification, reference being had to the accompanying drawings, showing a part thereof.

The leading feature of my design for a puzzle or game-board is a field having blocks with curved and right-lined sides forming circular and angular passages between said blocks and an inlet to and outlet from said passages.

Figure 1 represents a face view of a puzzle or game-board embodying my design. Fig. 15 2 represents a section on line xx , Fig. 1.

In the drawings, A designates the board, from the face of which rise the blocks B B, which are separated from each other, forming the passages C D, said board having also 20 the inlet E to said passage and the outlet F therefrom. The sides of the blocks are angular and curved, so that said passages are both circular and angular.

What I claim is—

25 The design for a game-board substantially as shown and described.

EMMA A. TOURNY.
